UNITED STATES PATENT OFFICE.

CHARLES A. HERMANN, OF MILWAUKEE, WISCONSIN.

PACKAGE-RECEPTACLE.

1,112,449.

Specification of Letters Patent.

Patented Oct. 6, 1914.

Application filed October 1, 1913. Serial No. 792,737.

To all whom it may concern:

Be it known that I, CHARLES A. HERMANN, a citizen of the United States, residing at Milwaukee, county of Milwaukee, 5 and State of Wisconsin, have invented new and useful Improvements in Package-Receptacles, of which the following is a specification.

My invention relates to that class of package receptacles which are adapted to contain milk, mail and other articles of merchandise, and to support the contained articles in a raised position protected from the elements and from the depredation of small 15 animals, such as dogs and cats.

The object of my invention is to provide a receptacle which can be easily and quickly manipulated to open or closed position by authorized persons, but in which the contents will be securely retained and protected 20 not only in the above mentioned particulars but also against changes of temperature.

In the drawings Figure 1 is a front elevation of a receptacle embodying my invention as it appears in open position, the swinging member being at an angle of 90° to its closed position. Fig. 2 is a sectional view drawn to a central vertical plane transverse to the back plate, the receptacle being 25 in closed position and a milk bottle being illustrated therein. Fig. 3 is a sectional view drawn to a horizontal plane on line $x-x$ of Fig. 2. Fig. 4 is a detail sectional view, illustrating the upper interlocking retaining flanges on an enlarged scale. Fig. 35 5 is a similar view showing the lower retaining flanges. Fig. 6 is a detail view showing a fragment of the swinging member in its relation to the hinge and the supporting pivotal extension. Fig. 7 is a detail fragmentary view showing the trick lock employed to prevent unauthorized persons from tampering with the contents of the receptacle. Fig. 8 is a sectional view 40 drawn on line $y-y$ of Fig. 7.

Like parts are identified by the same reference characters throughout the several views.

A wall plate 1 is provided with an offset 50 raised flange 2 at its upper end and a hook flange 3 at its lower end. One side margin of this plate is provided with an outwardly projecting flange 4 and the other side margin is provided with looped members 5 55 forming butts adapted to receive a hinge pintle 6. The wall plate 1 forms the back

wall of the receptacle. It is adapted to be secured to a wall or post by means of screws or bolts and will ordinarily be supported in a raised position. A sheet 8 of asbestos cloth, paper or other non heat conducting material is secured to the wall plate 1, preferably leaving the margin 9 of the wall plate uncovered. An order card 10 may be held against this wall plate with the sheet 60 8 interposed, so that when the receptacle is opened, the order card will be exposed to view. This order card is preferably removably held in position by a resilient wire holder 12, the lower ends of which are 65 riveted to the wall plate at 13. The upper end 14 of the holder is offset inwardly, whereby it may be grasped and pulled outwardly for the removal or replacement of an order card. The central portion of the 70 wire holder is preferably bowed as illustrated in Fig. 2. The remaining portions of the receptacle are in hinge connection with the pintle 6. A curved plate 15 of sheet metal forms the front and side walls 80 and cooperates with the wall plate 1 and with top and bottom plates 16 and 17 to form a complete inclosure. The top plate 16 is provided with a hooked flange 18, which is adapted to engage over the flange 85 2. The bottom plate 17 is provided with a down turned flange 20 which is adapted to engage in the hook flange 3, as shown in Fig. 2. These interlocking flanges 2 and 18 and 3 and 20 respectively, are also illustrated on a larger scale in Figs. 4 and 5. The bottom plate 17 is preferably inclined 90 outwardly so that the contents of the receptacle will not fall out when the latter is opened. The top plate 16 is also preferably inclined so that water will drain away instead of lodging on top of the receptacle. The swinging plate 15 is preferably provided with an asbestos lining 23.

In use, assuming the receptacle to be 100 closed as shown in Fig. 2, it may be readily opened by first lifting it until the hooked flange 18 disengages from the flange 2 and flange 20 disengages from hooked flange 3. The receptacle may then be swung to open 105 position, and in open position will be supported by an arm 25 projecting underneath the receptacle from the lower end of the hinge pintle 6. To prevent unauthorized persons from opening the receptacle, the 110 trick lock shown in Figs. 7 and 8 is provided. This comprises a spring actuated

latch 30, which is secured to the inner face of the wall 15 near that margin which laps upon the flange 4. The flange 4 is provided with an aperture 31, which is located in a position for registry with the latch head when the swinging member is raised to swinging position with the flanges 18 and 20 disengaged from the flanges 2 and 3 on the wall plate. When the receptacle is closed, the latch head will therefore be in the position relative to the aperture 31 in which it is shown in Figs. 7 and 8, said latch head being thus wholly concealed from view by the flange 4. The latch being fastened to the interior surface of the wall 15, it is obvious that it will not catch upon the flange 4 when the movable member is swung to closed position. The wall 15 is provided with an aperture 32 through which the latch head 30 projects, whereby it may pass into engagement in the aperture 31 when brought in registry therewith.

With the above described latch, if an unauthorized person who is also uninformed as to the structure of the cabinet attempts to open it, he will find no latch or lock to be manipulated. If he discovers that the movable member can be raised, he will still be unable to swing it to open position by reason of latch head 30 engaging in aperture 31. But as latch head 30 is not visible through aperture 31 except when the movable member is raised, it is assumed that it will not be discovered. One who understands the construction, however, can easily open the cabinet by first raising the movable member until the latch is exposed through the aperture 31 and then pressing inwardly upon the latch with a nail, pencil or other tool and simultaneously pulling outwardly upon the movable member to swing it to open position.

I claim—

1. A receptacle comprising the combination with a wall plate, of a package holding member, hinges connecting said member with the wall plate and having sufficient play to allow both vertical and swinging movements, and mutually interlocking flanges upon the wall plate and package holding member respectively, adapted to prevent the package holding member from swinging to open position except when raised.
2. A receptacle comprising the combination with a wall plate, of a swinging package holding member, hinges connecting said member with the wall plate; the butts of said hinges being spaced to permit vertical movements of said member, and mutually interlocking flanges upon the wall plate and

package holding member respectively, adapted to prevent the package holding member from swinging to open position except when raised, said hinge having a pintle provided at its lower end with a supporting arm adapted to hold the swinging member in a raised position when not in closed position.

3. A receptacle comprising the combination with a wall plate, of a package holding member, connections between one side margin of the package holding member and the wall plate, adapted to permit both lifting and swinging movements of said member, mutually interlocking flanges upon the wall plate and package holding member, respectively, adapted to prevent the package holding member from swinging to open position except when raised, an outwardly projecting apertured flange on the wall plate, and a latch on the package holding member located in a position to interlock in the flange aperture, when the package holding member is raised to a position disengaging said interlocking flanges preparatory to swinging said member to open position, said latch being out of registry with the flange aperture when the package holding member is closed and depressed with said flanges in interlocking position.

4. A receptacle comprising the combination with a wall plate, a package holding member, connections between one side margin of the package holding member and the wall plate, adapted to permit both lifting and swinging movements of said member, mutually interlocking flanges upon the wall plate and package holding member, respectively, adapted to prevent the package holding member from swinging to open position except when raised, said wall plate being provided with an interior order card holder.

5. A receptacle comprising the combination with a wall plate, of a package holding member, connections between one side margin of the package holding member and the wall plate adapted to permit both lifting and swinging movements of said member, and mutually interlocking flanges upon the wall plate and package holding member respectively, adapted to prevent the package holding member from swinging to open position except when raised, said wall plate and swinging member being provided with a lining of non-heat conducting material.

In testimony whereof I affix my signature in the presence of two witnesses.

CHARLES A. HERMANN.
